UNITED STATES PATENT OFFICE.

A. P. HAWSE AND L. J. ADAMS, OF MORRISVILLE, VERMONT.

SCRUBBING-PAIL.

Specification of Letters Patent No. 22,799, dated February 1, 1859.

To all whom it may concern:

Be it known that we, A. P. HAWSE and L. J. ADAMS, of Morrisville, in the county of Lamoille and State of Vermont, have invented a new and useful Improvement in 5 Scrubbing-Pails and Mop-Wringers; and we do hereby declare that the following is a full, clear, and exact description of the construction and operation of the same, reference being had to the annexed drawing, representing a perspective view of the pail and 10 mop-wringer and forming part of this specification.

In the drawing P is the pail, having two 15 upright pieces of iron a a' secured thereto, and extending upward, and constituting the bearings for a roller R. The lower portions of the pieces a a' extend in a bow form as seen at B from the bottom of the pail, giving 20 it a firm bearing at its base.

Crossing the pieces a a' , and connected therewith by two pins b, is a double-branched piece of metal C, whose upper extremities constitute the bearings for a second roller 25 R', whose natural position is in contact with the roller R as shown in the drawing, by reason of the weight of the bow portion D of the piece which extends outward along the floor as shown in the drawing. The rollers 30 R R' constitute the handle of the pail, by which it is transported, and in their natural

position permit the insertion of the mop on either side thereof.

To wring the mop, the toe of the operator is inserted under portion D of piece C, producing a movement of said piece about pins b and causing a separation of the rollers R R'. The mop is inserted between them, the feet of the operator are placed upon both bow pieces B and D and the mop is drawn 35 upward from between the rollers; the moisture being extracted therefrom by the pressure of the rollers. 40

This article is simple in construction combining the advantages of a common pail 45 mop wringer: the rollers performing the double function of pail handle and mop drier.

We make no claim to pressure rollers broadly considered as mop driers, but 50

We claim as our invention—

The combination of pail P, rollers R R', and pieces a a' and C, arranged and operating substantially as and for the purposes set forth. 55

In testimony, we have hereunto signed our names before two subscribing witnesses.

ASA P. HAWSE.

LUTHER J. ADAMS.
